UNITED STATES PATENT OFFICE.

JOHN FOURNIA, OF ALBANY, NEW YORK.

RAILWAY-TRAFFIC-CONTROLLING DEVICE.

1,177,941.

Patented Apr. 4, 1916.

Application filed February 12, 1913. Serial No. 747,856.

To all whom it may concern:

Be it known that I, JOHN FOURNIA, a citizen of the United States, residing at Albany, in the county of Albany and State of New York, have invented certain new and useful Improvements in Railway-Traffic-Controlling Devices, of which the following is a specification, reference being had therein to the accompanying drawings, forming part thereof.

My invention relates to railway traffic-controlling devices and particularly to that class of traffic-controlling devices which are known as automatic train stops.

An object of my invention is to provide a reliable controlling apparatus which will positively apply the brakes automatically at the proper and predetermined times, in such a way as to bring the train to a gradual stop without any sudden or unnecessary jar, and which will operate in this manner irrespective of the length of the train. In order to make the usual service application of the brakes in the common air-brake systems, the pressure in the train pipe is reduced a certain amount, usually about twenty pounds. In order to effect this reduction, the amount of air that is permitted to escape is dependent upon the length of the train pipe, being proportionate to the amount of air that is in the entire train pipe for the whole length of the train, and more air must, therefore, escape from a long train pipe to effect a given reduction than from a shorter train pipe. In accordance with my invention, I provide an equalizing device which is automatically operated and which opens a vent in the train pipe and holds the vent open until the pressure in the train pipe is reduced a predetermined amount, irrespective of the amount of air which escapes.

Another object of my invention is to provide an apparatus which will assure that the engineer will always be at his post, and that he will observe the automatic signals along the track. To this end I provide an automatic control which supplements, but does not dispense with, the human element required in the control of the train. In other words, absolute reliance is not had upon the automatic control, which would enable the engineer or other motorman to relax his

watchfulness, but, in accordance with my invention, the apparatus will operate to stop the train at each signal unless prevented by the engineer, and as a positive act is required on the engineer's part at each signal to prevent the automatic device from stopping the train, the likelihood of his passing a signal without observing it is minimized.

Another object of my invention is to provide means for preventing the engineer from operating his hold-out continuously, for any considerable length of time, and in accordance with my invention the apparatus is so constructed that the brakes will be automatically applied after the hold-out has been operated for a certain length of time.

Another object of my invention is to provide means for automatically shutting off the power from the motor, as by closing the throttle, at the same time that the brakes are applied and without moving the throttle bar or other lever under the manual control of the engineer.

Another object of my invention is to cause the apparatus to be tested at each signal, to assure that it is in working order, and the apparatus is so constructed that, with the exception of the actual brake-applying valve, it all goes through its entire operation at each signal after the engineer has performed the positive act required of him to prevent the brakes from being applied.

Another object of my invention is to provide an improved mechanical trip for the apparatus, one of which is located at each signal, which is so arranged and constructed as to be actuated by each wheel of a train which passes over the rail, thereby keeping the trip in good working order, and this trip preferably extends up through a perforation through the head of the rail at the side of the web, thereby weakening the rail to a negligible extent.

Another object of my invention is to provide an operating device for the automatic brake-applying apparatus, which is carried by the engine or other railway vehicle in proximity to the track in position to be engaged by the automatic tripping devices, and located between two wheels of the vehicle so that one wheel will always go in

advance of the operating device and clear the track of any foreign obstructions in the path of the operating device.

Another object of my invention is to so 5 mount the operating device that it will always maintain its correct relative distance from the rail, and to this end the operating device is directly supported by the axles of the wheels of the vehicle, and not by any 10 part which is mounted upon the springs and which varies its relative distance from the track.

Other general objects of my invention are 15 reliability of operation and simplicity of construction. Still other objects and advantages of my invention will appear from the following description.

I shall now describe the embodiments of 20 my invention illustrated in the accompanying drawings and shall thereafter point out my invention in claims.

Figure 1 is a diagrammatic representation 25 of my improved apparatus showing a part of a locomotive in outline and the apparatus correctly positioned thereon. Fig. 2 is a diagrammatic representation, partly in sectional elevation of my improved apparatus. Fig. 3 is an elevation, partly in section, of a portion of a rail and of my mechanical tripping device attached thereto and disposed in proper tripping relation to the apparatus shown in Fig. 2. Fig. 4 is a 30 transverse sectional elevation of the operating valve, taken on line 4-4 of Fig. 6. Fig. 35 5 is a bottom detail view of a rotary valve head showing the stem in section. Figs. 6 and 7 are central longitudinal sectional elevations of the operating valve showing the valve, respectively, in non-operating and in 40 operating positions. Fig. 8 is a diagrammatic view of an automatic signal and a portion of a track showing a modified form of mechanical trip and showing the magnetically controlled trip. Fig. 9 is a transverse 45 sectional detail on an enlarged scale of the rail showing the modified form of mechanical trip which is shown in Fig. 8.

The illustrated apparatus is connected 50 with the air brake system and is operated by the air pressure used in this system. A vent 1 is provided in a branch pipe 2 of the train pipe 3 and the train pipe is vented to reduce the pressure therein and apply the brakes by operating the brake-applying 55 valve device arranged in control of this vent 1. This brake-applying valve operates by equalizing pressures on opposite sides of an equalizing piston valve 4 in control of the vent 1 to hold the equalizing valve 4 closed when the pressures on its opposite 60 sides are substantially equal, and to be raised off its seat and open the vent when the pressure on its under side is excessive. The brake-applying valve includes two 65 chambers 5 and 6, the former of which is

termed a high pressure chamber, and the latter a low pressure chamber, and communication with which is controlled by a slide valve 7 which is adapted to reciprocate in the casing 8 of the brake-applying valve. 70 In the normal position of the slide valve 7, which is shown in Fig. 2, the chamber 5 communicates with the train pipe 3 through the branch pipe 2, passageway 9, bridging recess 10 in the slide valve 7 and passageway 11; and the chamber 6 communicates with an atmospheric port 12 through the passageway 13, and the bridging recess 14 in the slide valve 7. Communication between the main reservoir pressure line 15 and the engineer's valve 16 is provided 80 through a conduit including the pipe 17 leading into the upper part of the casing 8 of the brake-applying valve, and the pipe 18 which leads from the casing 8 to the engineer's valve 16. Main reservoir pressure is therefore provided upon the slide valve 7 which tends to hold the slide valve seated in any position to which it is moved.

With the slide valve in the position shown 90 in Fig. 2, the pressure upon the opposite sides of the equalizing valve 4 is equal, and since the exposed area of the upper side of the valve is greater than that of the lower side, the valve is seated under these conditions and holds the vent 1 closed. When the slide valve 7 is moved to the left, the bridging recess 10 in the slide valve is moved over so as to connect the passageways 11 and 13, and in this position of the valve, therefore, the two chambers 5 and 6 are connected while communication between the chamber 5 and the train pipe is interrupted and the communication between chamber 6 and the atmospheric port 12 is interrupted. 100 The pressure in the chamber 5 immediately falls until the pressure in the two chambers 5 and 6 is equal, and since the pressure upon the upper side of the equalizing valve 4 is thereby reduced, this equalizing valve is 110 raised off its seat by pressure on its under side, and the train pipe is vented until the pressure in the train pipe becomes substantially equal to that in the chambers 5 and 6, when the valve 4 is again seated and the vent closed. The amount of reduction 115 in pressure is, of course, determined by the relative volume of the two chambers 5 and 6, and this is fixed by the desired reduction. It is apparent that when the slide valve 7 is thus operated, the equalizing valve 4 holds the vent 1 open until the pressure in the train pipe has fallen the predetermined amount, irrespective of the amount of air 120 that must escape and effect this reduction. The brakes are applied in this manner very gradually and without any sudden jolt, or in other words, the usual service application of the brake is thus made. When the slide valve 7 is in this brake-applying position, 130

it closes off the port connecting with the pipe 18, and thereby closes off communication between the engineer's valve 16 and the main reservoir, and thus prevents the main reservoir pressure from passing into the train pipe and keeping up the train pipe pressure to running condition when the train pipe is vented.

To operate the brake-applying valve, 10 operating means are employed which are automatically operated by actuating means located along the railroad track, and in the embodiment shown a piston device is employed which is operated by air pressure 15 from the main reservoir line 15 and controlled by the operating means. In the specific apparatus shown the operating means is actuated by track instruments or mechanical tripping devices, but it is evident 20 that any suitable or well-known means could be employed for the actuation of the operating means. The piston device comprises a piston 19 which reciprocates in a cylinder 20 and is connected to the slide 25 valve 7 by a piston stem 21 and thereby transmits reciprocation to the slide valve 7. A conduit provides communication between the main pressure reservoir line 15 and to the cylinder 20, and includes branches leading 30 to opposite sides of the piston 19, and communication with these respective branches is controlled by the operating valve which is a rotary valve and is actuated by a track instrument as will hereinafter appear. This conduit includes the pipe 22 leading from the main reservoir pressure line 15 to the rotary valve, and from this rotary valve lead the two branches, one the pipe 23 leading to the cylinder 20 in front 35 of the piston 19 so that air entering from the pipe 23 will move the slide valve 7 to the position shown in Fig. 2, and the other consisting of the pipes 24 and 25 the latter of which leads behind the piston 19, and communication between which is controlled 40 by the manually actuated controlling valve hereinafter to be described.

The operating valve is a rotary valve which is shown in detail in Figs. 4, 5, 6 and 50 7. This rotary valve is actuated by a lever arm 26 which is fixed upon the stem 27 of the valve and which extends down in that position to be engaged by the track instruments as the train passes. Fixed upon this 55 stem is the rotary valve head 28 which rotates upon the valve seat 29. The valve seat 29 is provided with two pressure passageways 30 and 31, and with an atmospheric passageway 32, and the pressure passageways 30 and 31 are connected to the pipes 23 and 24 respectively. The pipe 22 communicates with the port 33 in the cap 34 of the operating valve and the main reservoir pressure enters this port 33 and envelops the 60 rotary valve head 28 and passes out of the

passageway 30 through a port 35 in the rotary valve head or out of the passageway 31 according to the position of the rotary valve head 28. In the normal position of the rotary valve head the port 35 registers 70 with the passageway 30 as shown in Fig. 6, and main reservoir pressure therefore normally passes through the pipe 23 into the cylinder 20 in front of piston 19. The rotary valve head 28 is cut out on its two 75 opposite sides as shown in Figs. 4 and 5, providing a central portion which in the normal position of the rotary valve head over-lies the entrance to the passageway 31 and closes this means of communication between this passageway 31 and the port 33. The under side of the rotary valve head is provided with a recess 36 which furnishes communication between the passageway 31 and the atmospheric passageway 32 in the 80 normal position of the valve head, as shown in Fig. 6. This recess 36 is provided with two radial extensions 37 on opposite sides of the port 35, and as shown in Fig. 7, these recess extensions 37 provide communication 85 between the passageway 30 and the atmospheric passageway 32, as the rotary valve is rotated by engagements with the track instruments. It will be noted that communication will be provided as above described 90 when the rotary valve head is actuated, irrespective of the direction in which the train is moving since there are two cut away portions and two recess extensions 37, and one of each of these will be brought into 95 service when the valve is rotated in one direction and the other when the valve is rotated in the opposite direction.

It will now be understood that in the normal or non-operating position of the operating valve, as shown in Figs. 1, 2, 4 and 6, main reservoir pressure is being admitted through the pipe 23 in front of the piston 19, while the space behind, being connected to the atmospheric passageway 32 through 100 the pipes 25 and 24, the passage 31 and the recess 36, is at atmospheric pressure; and that when the lever arm 26 is actuated and the valve 28 is rotated, these connections are reversed, and the pipe 23 is connected with the atmospheric passageway 32, and pipes 24 and 25 are connected with the main reservoir pressure. If nothing operates to prevent communication between the pipes 24 and 25, the main reservoir 110 pressure will operate to move the piston 19 and hence the slide valve 7 to the position opposite that shown in Fig. 2 and the brakes will be applied in the manner heretofore described. To prevent the application of the 115 brakes, however, manually controlled means are provided under the control of the engineer by which communication between the pipes 24 and 25 is prevented, and the main reservoir pressure which is admitted to the 120

pipe 24 is diverted to effect the operation of a restoring device to restore the operating valve to its normal position, as will now be described.

- 5 Located within the cab within convenient reach of the engineer is the controlling valve, which comprises a slide valve 38 reciprocative in a valve casing 39. Main reservoir pressure is admitted through the pipe 10 near the top of the casing 39, and this pressure fluid envelops the slide valve 38 and holds it seated and in the position to which it is moved. Secured to a rearwardly extending stem 41 on this slide valve is an 15 operating handle 42 pivoted at its lower end and connected with a treadle member 43 whereby the stem 41 can be reciprocated either by foot or by hand. The handle 42 is provided with a stop 44 which engages 20 a latch 45 in the normal position of the latch, as shown in Fig. 2, after the handle 42 has been moved a short distance. This latch 45 has on its lower end the piston 46 25 slidable in a cylinder 47, and this piston is normally held in an elevated position by a spring 48, and is withdrawn by fluid pressure admitted to the upper side of the piston 46, as will hereafter appear.
- In the normal position of the slide valve, 30 shown in Fig. 2, a bridging passageway 49 provides communication between the pipes 24 and 25, but as the engineer moves the handle 42, or treadle 43, until the stop 44 engages the latch 45, he thereby moves the 35 slide valve 38 sufficiently to connect the pipe 25 with an atmospheric port 50 in the casing 39, and to connect the pipe 24 with a pipe 51 which has two branches, one branch 52 leading to the upper side of the latch 46, and the other branch 53 leading 40 behind a piston 54 connected by a stem 55 with the slide valve 38, and reciprocated in a cylinder 56. The air thus admitted to the pipe 51 from the pipe 24 serves both to retract the latch 45 from the path of the stop 44 and to complete the movement of the slide valve 38 by the pressure fluid admitted behind the piston 54. It will therefore be seen 45 that the engineer merely initiates the operation of the controlling valve and that thereafter its operation is automatically completed. This further automatic movement of the slide valve serves to operate a restoring device for the operating valve to restore 50 the apparatus to its normal running condition, and also to admit pressure fluid in front of the piston 54 to restore the control valve to its normal position, as will now be described.
- 55 The restoring device is located directly above the operating valve and both are carried upon a plate 57 secured at its end to the boxes 58 of the drive wheels of the locomotive. Being thus carried by the same member the relative distance between the

two is always the same, and since they are both supported upon the axles of the locomotive the relative distance between the lever arm 26 and the rail is always the same, there being no spring to yield and vary this 70 relative distance. It will be readily understood that it is important to keep this relative distance constant in order that the operating device will positively be engaged and actuated by the track instruments. 75 Since the other parts of the apparatus are mounted upon the spring supported superstructure of the locomotive, it is essential to provide flexibility in the pipe connections between the yielding and the rigid parts of 80 the apparatus, and this may be provided in any suitable way, as by flexible pipe sections, as shown in Fig. 1. The operating valve is disposed directly over the rail, and inasmuch as the track instruments will usually 85 be provided in the rails in only one side of the track, the operating valve and restoring device will be duplicated on both sides of the locomotive to assure operation by the track instruments in whichever way the 90 locomotive is going upon the track, these 95 duplicated parts not being shown to avoid confusion of illustration. It will be noted that the operating valve is arranged between the two drive wheels of the locomotive, with the result that one wheel always precedes the lever arm 26, and clears the track of any foreign obstruction in the path of the operating lever.

The restoring device comprises two diverging arms forming an inverted V-shaped device 57 disposed directly above the upper end of the lever 26 carried upon the downward extending stem 58 on a vertically sliding piston 59 which reciprocates in a 100 cylinder 60. This piston 59 and connected parts are normally maintained in elevated position by a spring 61, and by air pressure which enters through a pipe 62 which enters the cylinder 60 on the under side of the 105 piston 59, and communicates with the port in the casing 39 of the controlling valve with which a transverse slot 63 in the slide valve 38 normally registers. Main reservoir pressure which envelops the slide valve 38 normally passes through this slot 63 and thence through the pipe 62 to the under side of the 110 piston 59 and supplements the spring 61.

To depress the piston 59 and restore the operating valve, fluid pressure is admitted 115 upon the upper side of the piston 59 through the pipe 64 and under the control of the controlling slide valve 38. This pipe 64, in the normal position of the slide valve, communicates with a longitudinal passageway 120 65 in the slide valve which communicates with the atmospheric port 50 as long as the slide valve is in such position that the passageway 65 communicates with the pipe 64. It is therefore apparent that in the normal 125

condition of the apparatus, the space above the piston 59 is vented to the atmosphere. After the movement of the slide valve 38 has been manually initiated and the pressure fluid from the pipe 24 diverted into the pipe 51, the movement of the slide valve 38 is completed by the pressure fluid entering into the pipe 53 behind the piston 54 in the manner above described. This further movement of the slide valve 38 brings the slot 63 into register with the port leading to the pipe 64 and pressure fluid from the pipe 40 is thereby admitted through the pipe 64 above the piston 59. At the same time the port leading to the pipe 62 is brought into communication with a bridging recess 66 on the under side of the slide valve 38, which communicates through a port on its upper side with the passageway 65, and is thereby vented to the atmosphere through the atmospheric port 50, the slide valve 38 being provided with a recess 67 at the end of the passageway 65 which is of such length that the passageway 65 is in communication with the atmospheric port 50 throughout the entire range of movement of the slide valve 38. Since pressure fluid is admitted to the upper side of the piston 59 and the space below the piston 59 is at the same time vented to the atmosphere through the connection thus described, the restoring device is depressed, and the lever arm 26 is restored to its vertical position by the V-shaped member 57, and the operating valve is restored to its normal position. The pipe 24 is thereby again connected with the atmospheric passageway 32 in the operating valve, and hence the space behind the piston 54 and the space above the piston 46 are vented to the atmosphere, and the operating valve is ready to be restored to its normal position, through the means now to be described.

A conduit connects the cylinder 56 in front of the piston 54 with the pipe 22, and the valve in this conduit is controlled by the final movement of the restoring mechanism. The piston 59 is provided with an upwardly extending stem 68 which projects into the cylinder 69 and is slotted as shown in Fig. 52, and in this slot engages a pin on a slide valve 70. This slide valve 70 is provided with a bridging recess 71 which in the normal position of the slide valve, provides communication between an atmospheric port 72 and a port leading to a pipe 73 which leads to the cylinder 56 and which forms one part of the conduit providing communication between the pipe 22 and the cylinder 56, while the pipe 74 which connects the cylinder 69 with the pipe 22 forms the other part of the conduit. The main reservoir pressure continually enters this cylinder 69 through this pipe 74 and envelops the slide valve 70 and maintains this

slide valve upon its seat and holds it in adjusted position. It will be noted that the space in front of the piston 54 is normally vented to the atmosphere through the pipe 73, recess 71 and atmospheric port 72, so that the piston 54 and the slide valve 38 connected thereto are free to be moved to the right as above described. After the restoring device has been depressed, however, sufficiently to restore the operating valve, the upper end of the slot in the stem 68 engages the pin on the slide valve 70 and the fluid pressure entering through the pipe 64 continues to depress the restoring device, this continued movement being permitted by a slot 75 formed at the top of the restoring member at the juncture of the two diverging arms as shown. The further downward movement of the restoring device serves to move the slide valve 70 down until communication is provided between the cylinder 56 and the pipe 22 through the pipes 73 and 74, and fluid pressure thus enters in the front of the piston 54 and moves the controlling slide valve 38 back to its original position as shown in the drawing. As soon as the slide valve 38 reaches this position, the slot 63 is again brought into register with the port leading to the pipe 62 and fluid pressure enters underneath the piston 59 and cooperates with the spring 61 to again raise the restoring device to its normal position, the space above the piston 59 being again vented to the atmosphere through the pipe 64, passageway 65, and atmospheric port 50.

It will now be understood that as the lever arm 26 is actuated by the track instruments, fluid pressure will be admitted to the piston actuating device of the brake-applying valve mechanism to actuate the same and apply the brakes unless this is prevented by the controlling valve as manually initiated and is automatically completed and its initial movement serves to divert the fluid pressure from the brake-applying valve mechanism to the piston mechanism which completes the operation of the controlling valve; and that in its final movement the controlling valve admits pressure fluid to the restoring device which restores the operating valve to its original position, and the restoring device in its final movement restores the controlling valve to its original position and thereby shuts off the fluid pressure from the restoring device which then assumes its original position. It will thus be observed that the operating valve, the controlling valve, and the restoring devices perform their complete operation each time that the movement of the controlling valve is initiated, and hence the engineer can be continually apprised of the condition of the apparatus.

To prevent the engineer from continually

holding the handle 42 forward so that the above described operations will automatically take place when the lever arm 26 is actuated, and thus permit him to relax his 5 vigilance, the controlling valve is so constructed that at the beginning of its movement it both opens a port in the main reservoir pressure line and shuts off the steam from the compressor. At this port may be 10 provided a whistle 76, as shown, the port being located in the casing 39 of the controlling valve in such position that it is normally covered by the slide valve 38 but is uncovered at the beginning of the movement 15 of the slide valve and permits the pressure fluid which enters through the pipe 40 to escape through the whistle 76 thereby giving an audible alarm. At the same time the steam pipe 77 for the compressor 78 which 20 compresses the air stored in the main reservoir 79, passes through a cylinder 80 in which is provided a piston 81 on the stem 41, which piston is arranged to close off communication through the cylinder 80 at the initial 25 movement of the stem 41 and slide valve 38. The initial movement of the slide valve, therefore, both serves to open a vent whereby the main reservoir pressure may fall, and to shut off the compressor so that the air is 30 no longer compressed and stored in the main reservoir 79. The air pressure thereby falls and the brakes are applied in the same manner as is effected by the operation of the engineer's valve.

35 In addition to applying brakes when the operating valve is actuated, means may also be provided for shutting off the throttle, and I have illustrated such means, which are operated by fluid pressure admitted through 40 a branch pipe 82 leading off from the pipe 25. The throttle stem 83 has a piston 84 formed on one end which reciprocates in a cylinder 85 to which the pipe 82 leads, and the pressure fluid which enters through the 45 pipe 82 serves to operate the piston and shut off the throttle. In order that this movement of the throttle stem may be effected without moving the throttle bar or operating lever 86 the throttle bar is releasably 50 connected to the throttle stem and is released therefrom at the same time the throttle stem is moved. The throttle stem is provided with a slot 87 in which the throttle bar engages and a spring pressed 55 latch 88 normally extends in front of the throttle bar as shown in Fig. 2, and locks the throttle bar to the throttle stem. On the end of this latch 88 is provided a latch piston 89 which reciprocates in a cylinder 60 90 formed on the throttle stem, and a spring 91 behind the piston 89 tends to maintain the latch in latching position, while the cylinder in front of the piston 89 communicates through a passageway 92 in the 65 throttle stem with the piston end of the

throttle stem, with the result that the pressure fluid which enters the cylinder 85 and operates the throttle stem also passes through the passageway 92 and retracts the latch 88 and releases the throttle bar 86 so 70 that the throttle stem is moved independently of the throttle bar. Any likelihood of injury to the engineer resulting from the unexpected movement of the throttle bar is thereby eliminated. It will of course be observed that the operation of the controlling valve serves to divert the pressure fluid from the throttle control at the same time that it is diverted from the brake-applying valve, and if the throttle has been shut off the latch 88 is returned by the spring 91 as soon as the pressure fluid is diverted, and the engineer has only to move the throttle bar 86 forward until it again latches to the throttle stem, and he then has complete control of 85 the throttle. It will be understood that by the term throttle, herein, I comprehend any power control.

80 Turning now to the specific form of actuating means for the controlling valve: This 90 is shown as a mechanical trip, and two embodiments thereof are shown. In Figs. 1 and 3 this is shown as a pivoted lever 93 which is pivoted to the web of the rail 94, and has an upwardly projecting finger 95 95 which projects through a perforation in the head of the rail at the side of the web, and a coiled spring 96 is arranged underneath the free end of the lever 93 and bears against the base of the rail and tends to 100 maintain the finger 95 in protruding position where it will strike the end of the lever arm 26. This is all inclosed in a casing 97 which serves to exclude the dirt and snow and other foreign matter. This perforation 105 in the head of the rail through which the finger 97 protrudes weakens the rail to a negligible extent, and this location of the tripping finger has the advantage that it is engaged and depressed by each wheel that 110 passes over it and, being thus frequently operated, is maintained in proper working condition.

115 In Figs. 8 and 9 a modification of this mechanical tripping device is shown. This modified construction differs from that already described in that instead of the finger being mounted upon a pivoted lever, a substantially round rod 98 is employed which is vertically slidable in the perforation provided for it in the head of the rail, and has a head 99 formed on its lower end underneath which a spring 100 bears and tends to 120 maintain the tripping finger in protruding position. A movable guide rod 101 for the 125 spring may be used. One of these mechanical tripping devices is located at each signal, as shown in Fig. 8, so that the operating valve is actuated at each signal post, irrespective of the position of the signal. 130

It will, therefore, be noted that unless the engineer operates the controlling valve and prevents the operation of the brakes, the brakes will be applied at each signal, and 5 since he has this positive act to perform at each signal, he is required to stay at his post in order to keep his train going, and since his attention is thus forcibly called to the fact that he is passing the signal, the likelihood 10 of his passing it without observing it is reduced to a minimum. In actual practice the engineer will operate his controlling device each time just before the operating valve is actuated, so that the pressure fluid 15 which passes through the pipe 24, instead of operating the brake-applying mechanism, will operate to complete the movement of the controlling valve, whereby the restoring device is actuated and the parts re- 20 stored to their normal positions.

As an additional precaution I prefer also to locate somewhat in advance of each signal a magnetically controlled tripping device in series with the signal actuating mechanism, as shown in Fig. 8, although this additional precaution may be dispensed with. In this construction the vertically sliding tripping finger 102 is held in tripping position by the coiled spring 103 surrounding 30 its lower end, and upon this finger underneath the rail 94 is provided an armature 104 directly above electro-magnets 105 which are connected by wires 106 and 107 in series with the electric motor, or other electrical actuating mechanism 108 for the signal. This mechanism is diagrammatically shown in the Fig. 8. As is well known to those skilled in the art, the signal actuating mechanism 108 is, in common practice, energized to hold the semaphore at clear, and when it is deenergized the semaphore falls by gravity to danger. When the signal actuating mechanism is thus energized, the electro-magnets 105 will also be energized 40 and the finger 102 will be retracted so that it will not actuate the lever arm 26. When the signal actuating mechanism is deenergized, however, the electro-magnets 105 will be deenergized and the finger 102 will be held in protruding position by the spring 103. If the engineer runs by a danger signal, he will therefore get a second actuation 45 when he reaches this second track instrument. It sometimes occurs that the signal actuating mechanism has been deenergized, and under such conditions the finger 102 will protrude and the engineer, upon getting the actuation from this finger, will be 50 apprised of the fact that he received a false clear indication at the signal just passed. It will be apparent that the electro-magnets 105 can be connected in series with the actuating mechanism for either the home signal 55 or the distant signal.

It is obvious that the various modifications may be made in the constructions shown in the drawings and above particularly described within the principle and scope of my invention.

70

I claim:

1. Controlling apparatus for railway trains comprising, in combination with the train pipe and a source of pressure fluid, a train pipe chamber normally communicating with the train pipe, a low-pressure chamber having normally lower pressure therein than that in the train pipe, an equalizing valve in control of a train pipe vent to close the vent when the pressures in the train pipe and in the train pipe chamber are substantially equal and to open the vent when the pressure in the train pipe exceeds that in the train pipe chamber, and means for shutting off communication between the train pipe and train pipe chamber and for establishing communication between the two chambers, whereby the pressure in the two chambers may become equal and the equalizing valve open the vent and permit the train pipe pressure to become equal to that of the two chambers.

2. Controlling apparatus for railway trains comprising, in combination with the railway track and the train pipe and a source of pressure fluid, a train pipe chamber normally communicating with the train pipe, a low-pressure chamber having normally lower pressure therein than that in the train pipe, an equalizing valve in control of a train pipe vent to close the vent when the pressures in the train pipe and in the train pipe chamber are substantially equal and to open the vent when the pressure in the train pipe exceeds that in the train pipe chamber, valve mechanism for shutting off communication between the train pipe and train pipe chamber and for establishing communication between the two chambers, and means located along the railway track and operative to actuate the valve mechanism as the train passes, whereby the pressure in the two chambers may become equal and the equalizing valve open the vent and permit the train pipe pressure to become equal to that of the two chambers.

3. Controlling apparatus for railway trains comprising, in combination with the railway track and the train pipe and a source of pressure fluid, a train pipe chamber normally communicating with the train pipe, an equalizing valve in control of a train pipe vent to close the vent when the pressures in the train pipe and in the train pipe chamber are substantially equal and to open the vent when the pressure in the train pipe exceeds that in the train pipe chamber, valve mechanism for shutting off communication between the train pipe and train pipe chamber and for reducing the pressure in

- the train pipe chamber a predetermined amount, and means located along the railway track and operative to actuate the valve mechanism as the train passes, whereby the pressure in the train pipe chamber is reduced the predetermined amount and the equalizing valve opens the vent and permits the train pipe pressure to become equal to that of the train pipe chamber.
4. Controlling apparatus for railway trains comprising, in combination with the railway track and the train pipe and a source of pressure fluid, a train pipe chamber normally communicating with the train pipe, an equalizing valve in control of a train pipe vent to close the vent when the pressures in the train pipe and in the train pipe chamber are substantially equal and to open the vent when the pressure in the train pipe exceeds that in the train pipe chamber, a brake-applying valve mechanism controlled by the pressure fluid and operative to shut off communication between the train pipe and the train pipe chamber and to reduce the pressure in the train pipe chamber a predetermined amount, an operating valve arranged to admit pressure fluid to the brake-applying valve mechanism to operate the same, and means located along the railway track and operative to actuate the operating valve as the train passes.
5. Controlling apparatus for railway trains, comprising, in combination with the railway track and the train pipe and a source of pressure fluid, a train pipe chamber normally communicating with the train pipe, a low-pressure chamber having normally lower pressure therein than that in the train pipe, an equalizing valve in control of a train pipe vent to close the vent when the pressures in the train pipe and in the train pipe chamber are substantially equal and to open the vent when the pressure in the train pipe exceeds that in the pipe chamber, a brake-applying valve mechanism controlled by the pressure fluid and operative to shut off communication between the train pipe and the train pipe chamber and to establish communication between the two chambers, an operating valve arranged to admit pressure fluid to the brake-applying valve mechanism to operate the same, and means located along the railway track and operative to actuate the operating valve as the train passes.
6. Controlling apparatus for railway trains comprising, in combination with the railway track and the train pipe and a source of pressure fluid, a brake-applying valve mechanism controlled by the pressure fluid and operative to reduce the pressure in the train pipe, a conduit connecting the source of pressure fluid with the brake-applying valve mechanism and arranged to conduct pressure fluid to the brake-applying valve mechanism to operate the same, a normally

closed operating valve in the conduit, means located along the railway track and operative to open the operating valve as the train passes, restoring mechanism operative to close the operating valve, and manually controlled means for closing the conduit independently of the operating valve and for operating the restoring mechanism.

7. Controlling apparatus for railway trains comprising, in combination with the railway track and the train pipe and a source of pressure fluid, a brake-applying valve mechanism controlled by the pressure fluid and operative to reduce the pressure in the train pipe, a conduit connecting the source of pressure fluid with the brake-applying valve mechanism and arranged to conduct pressure fluid to the brake-applying mechanism to operate the same, a normally closed operating valve in the conduit, means located along the railway track and operative to open the operating valve as the train passes, restoring mechanism controlled by pressure and operative to close the operating valve, and manually controlled means for closing the conduit independently of the operating valve and for admitting pressure fluid to the restoring mechanism to operate the same.

8. Controlling apparatus for railway trains comprising, in combination with a railway track and the train pipe and a source of pressure fluid, valve means adapted to reduce the pressure in the train pipe, means located along the railway track and operative to actuate the valve mechanism, pressure fluid operated restoring mechanism operative to restore the valve mechanism, a controlling valve operative only at the end of its movement to admit pressure fluid to the restoring mechanism, manually operated means for initiating the movement of the controlling valve, and automatic means for completing the movement of the controlling valve.

9. Controlling apparatus for railway trains comprising, in combination with a railway track and the train pipe and a source of pressure fluid, a brake-applying valve mechanism controlled by the pressure fluid and operative to reduce the pressure in the train pipe, a conduit connecting the source of pressure fluid with the brake-applying valve mechanism and arranged to conduct pressure fluid to the brake-applying valve mechanism to operate the same, a normally closed operating valve in the conduit, means located along the railway track and operative to open the operating valve as the train passes, restoring mechanism operative to close the operating valve, and a normally open controlling valve arranged in control of the conduit and operative at the beginning of its movement to close the conduit and in the latter part of its movement to operate the restoring valve.

10. Controlling apparatus for railway trains comprising, in combination with a railway track and the train pipe and a source of pressure fluid, a brake-applying valve mechanism controlled by the pressure fluid and operative to reduce the pressure in the train pipe, a conduit connecting the source of pressure fluid with the brake-applying valve mechanism and arranged to conduct pressure fluid to the brake-applying valve mechanism to operate the same, a normally closed operating valve in the conduit, means located along the railway track and operative to open the operating valve as the train passes, restoring mechanism operative to close the operating valve, a normally open controlling valve arranged in control of the conduit and operative at the beginning of its movement to close the conduit and in the latter part of its movement to operate the restoring valve, a normally open controlling valve arranged in control of the conduit and of the restoring mechanism, pressure fluid operated means for actuating the controlling valve, and manually operated means for initiating the movement of the controlling valve, the controlling valve being constructed to divert pressure fluid from the conduit to the means for operating the controlling valve, whereby the movement of the controlling valve is completed to operate the restoring mechanism.

11. Controlling apparatus for railway trains comprising, in combination with the railway track and the train pipe and a source of pressure fluid, a brake-applying slide valve mechanism arranged in control of the pressure in the train pipe and a piston mechanism for operating the same, an operating valve, a conduit connecting the operating valve with the source of pressure fluid, two branch conduits connecting the operating valve with the piston mechanism and leading to opposite sides thereof, the operating valve being constructed to admit pressure fluid through one branch conduit in its normal position and to admit pressure fluid through the other branch conduit when moved away from its normal position, and means located along the railway track and operative to actuate the operating valve as the train passes.

12. Controlling apparatus for railway trains comprising, in combination with the railway track and the train pipe and a source of pressure fluid, a brake-applying slide valve mechanism arranged in control of the pressure in the train pipe and a piston mechanism for operating the same, an operating valve, a conduit connecting the operating valve with the source of pressure fluid, two branch conduits connecting the operating valve with the piston mechanism and leading to opposite sides thereof, the operating valve being constructed to admit pressure fluid through one branch conduit in its nor-

mal position and to admit pressure fluid through the other branch conduit when moved away from its normal position, means located along the railway track and operative to actuate the operating valve and move it away from its normal position as the train passes, and manually controlled means for closing communication between the operating valve and the piston mechanism of the brake-applying valve mechanism through the second branch conduit.

13. Controlling apparatus for railway trains comprising, in combination with the railway track and the train pipe and a source of pressure fluid, a brake-applying slide valve mechanism arranged in control of the pressure in the train pipe and a piston mechanism for operating the same, an operating valve, a conduit connecting the operating valve with the source of pressure fluid, two branch conduits connecting the operating valve with the piston mechanism and leading to opposite sides thereof, the operating valve being constructed to admit pressure fluid through one branch conduit in its normal position and to admit pressure fluid through the other branch conduit when moved away from its normal position, means located along the railway track and operative to actuate the operating valve and move it away from its normal position as the train passes, restoring mechanism operated to restore the operating valve to normal position, and manually controlled means for actuating the restoring mechanism.

14. Controlling apparatus for railway trains comprising, in combination with the railway track and the train pipe and a source of pressure fluid, a brake-applying slide valve mechanism arranged in control of the pressure in the train pipe and a piston mechanism for operating the same, an operating valve, a conduit connecting the operating valve with the source of pressure fluid, two branch conduits connecting the operating valve with the piston mechanism and leading to opposite sides thereof, the operating valve being constructed to admit pressure fluid through one branch conduit in its normal position and to admit pressure fluid through the other branch conduit when moved away from its normal position, means located along the railway track and operative to actuate the operating valve and move it away from its normal position as the train passes, restoring mechanism controlled by pressure fluid and operative to restore the operating valve to normal position, a controlling valve and fluid pressure operated actuating means therefor, the controlling valve being related to the second branch conduit and arranged to divert the pressure fluid in this branch conduit at the beginning of its movement to the actuating means of the controlling valve and during

its further movement to admit pressure fluid to the restoring mechanism, and manually operated means for initiating the movement of the controlling valve.

- 5 15. Controlling apparatus for railway trains comprising, in combination with a railway track and the train pipe and a source of pressure fluid, a brake-controlling valve mechanism operative to reduce the pressure in the train pipe and apply the brakes, means located along the railway track and operative to actuate the valve mechanism as the train passes, restoring mechanism controlled by pressure fluid and operative to restore the brake-controlling valve mechanism to normal position, a manually actuated controlling valve operative to admit pressure fluid to the restoring mechanism to operate the same, a piston device 20 operative to return the controlling valve to normal position, a conduit providing communication between the piston device and the source of pressure fluid for conducting pressure fluid to operate the piston device, 25 and a valve in the conduit controlled by the restoring mechanism.

16. Controlling apparatus for railway trains comprising, in combination with a railway track and the train pipe and a source of pressure fluid, a brake-controlling valve mechanism operative to reduce the pressure in the train pipe and apply the brakes, means located along the railway track and operative to actuate the valve mechanism as the train passes, restoring mechanism controlled by pressure fluid and operative to restore the brake-controlling valve mechanism to normal position, a manually actuated controlling valve operative to 30 admit pressure fluid to the restoring mechanism to operate the same, a piston device 35

operative to return the controlling valve to normal position, a conduit providing communication between the piston device and the source of pressure fluid for conducting 45 pressure fluid to operate the piston device, and a valve in the conduit controlled by the restoring mechanism, the valve and restoring mechanism having lost motion connection, whereby the valve is opened only after 50 the restoring mechanism has restored the brake-controlling valve mechanism to normal position.

17. Controlling apparatus for railway trains comprising, in combination with the railway track and the train pipe and a source of pressure fluid, a brake-applying valve mechanism controlled by the pressure fluid and operative to reduce the pressure in the train pipe and to shut off the supply 60 of pressure fluid to the train pipe, a conduit connecting the source of pressure fluid with the brake-applying valve mechanism and arranged to conduct pressure fluid to the brake-applying mechanism to operate 65 the same, a normally closed operating valve in the conduit, means located along the railway track and operative to open the operating valve as the train passes, restoring mechanism controlled by pressure and operative to close the operating valve, and manually controlled means for closing the conduit independently of the operating valve and for admitting pressure fluid to the restoring mechanism to operate the same. 70 75
